UNITED STATES PATENT OFFICE.

CHARLES LINUS TENNEY, OF FITCHBURG, MASSACHUSETTS, ASSIGNOR OF ONE-HALF TO ALBERT SAWYER, OF SAME PLACE.

COUNTER-STIFFENER MACHINE.

SPECIFICATION forming part of Letters Patent No. 380,464, dated April 3, 1888.

Application filed July 30, 1887. Serial No. 245,737. (No model.)

To all whom it may concern:

Be it known that I, CHARLES LINUS TENNEY, a citizen of the United States, residing at Fitchburg, in the county of Worcester and 5 State of Massachusetts, have invented a new and useful Counter-Stiffener Machine, of which the following is a specification.

My invention relates to improvements in counter-stiffener machines by which stiffeners 10 are formed from blanks of leather and other materials into such shapes as are required in the manufacture of shoes; and the objects of my improvements are to form counters in a more simple and expeditious manner than has 15 been done heretofore, and consequently to cheapen their cost. I attain these objects by the mechanism illustrated in the accompanying drawings, in which—

Figure 1 is a side elevation of the entire machine; Fig. 2, a vertical section through the same on the line 1 2. Fig. 3 is a detail section, on an enlarged scale, of a portion of that outside of and on the line 3 4. Fig. 4 shows a stiffener-blank, and Fig. 5 a finished stiffener.

Similar letters refer to similar parts throughout the several views.

The frame A supports the whole of the machinery, and both sides present the same appearance. In the bearings a shaft, B, turns, 30 carrying a wheel, C, which is keyed fast midway between the bearings. The shaft extends beyond one of the bearings for power attachment, as may be desired. In the center of the periphery of the wheel, at regular intervals 35 apart, former-blocks D are fastened, of the shape and size to which it is desired that stiffeners shall conform, with the heel or rounded part leading in the same direction that the wheel is to turn.

Upon the top of the frame A, on each side 40 of the wheel, cellular boxes E are fastened, almost touching the edges of the wheel-face. The cells in these boxes range on a line parallel to and a little beyond the circumference of the wheel, with their axes at right angles to its plane. Their open ends are toward the wheel and opposite, each to each, those on the opposite sides of the frame. Fitted into each cell is a sliding block, F, Figs. 2 and 3, free to 45 move endwise only, its outer end rounded and

shaped to rub the surface of the former-blocks in the wheel, and of such length as will reach the center line of former-blocks when pushed out to its farthest range of motion.

A spring, a, contained in a cavity of the sliding block, abutting at one end the bottom of the cavity and at the other a cap, b, over the end of a cylindrical screw, c, in the closed end of the cell by which its force is regulated, opposes with yielding resistance any pressure 55 upon the outer end of the block.

The limit for the motion of the block is determined by the adjustment of binding-nuts against the outer end of the cylindrical screw c, and upon a rod, d, which passes through 60 the cylindrical screw c, cap b, and spring a, fastening into the sliding block at the end of the cavity.

The side cellular boxes, E E, are connected throughout their entire length by a top cellular box, G, which is fastened upon them. The cells in this box range on lines parallel with the plane of the wheel, with their axes on radial lines through the center of its face. The open ends are toward the wheel, and hold in 70 position a plate, H, by means of projections from it fitting into the cells. The plate H extends throughout the length of the box, and is nearly as wide as the space between the side boxes. The under side is corrugated diagonally from the center to each edge in a direction opposite to that of the wheel's motion. (See Fig. 3.) It is free to move toward the face of the wheel only, the projections into the cells preventing other motion; but against 75 endwise motion there is further provision by means of a lug, e, Fig. 1, at the end of the box. In the cells on top of the projections from the plate H there are rubber springs f, which oppose pressure upon the under side of the plate 80 in the same manner as the springs in the sliding blocks. Their force is regulated by means of set-screws g in the ends of the cells. Through the flange part of the box G are screws h, fitting loosely and threaded into the plate H to 85 limit its motion toward the wheel.

The operation of the machine is as follows: Blanks for stiffeners being placed by hand or otherwise upon the shelf I, across the face of the wheel in front of the former-blocks D, as 90

50

100

they are about to enter between the ends of the sliding blocks F and under the corrugated plate H in such position that the center of their length shall approximately coincide with the center line of former-blocks, the rounded edges upon the face of the wheel, and broad-sides against the points in the leading ends of former-blocks, the wheel in its revolution carries them along to be turned back upon the former-blocks by the resistance of the sliding blocks and corrugated plate, the sliding blocks acting successively on increasing extents of surface, shaping and rubbing down the part lying against the leading ends and sides of former-blocks, and the plate to turn inward and rub down upon the tops of the former-blocks the part allowed for flange, thus completing the formation of a stiffener by one passage through the machine, delivering them from the spout J in the form shown by Fig. 5.

What I claim, and desire to secure by Letters Patent of the United States, is—

1. In a counter-stiffener machine, the combination, with the wheel having former-blocks upon its periphery, of the yielding sliding

blocks and corrugated plates arranged with reference to each other, substantially as specified.

2. The combination, in a counter-stiffener machine, of the wheel C, having former-blocks 30 upon its periphery, with sliding blocks F and corrugated plate H, substantially as specified.

3. The combination, in a counter-stiffener machine, with a wheel having former-blocks 35 upon its periphery, of a series of yielding sliding blocks mounted on each side of said wheel and arranged to act successively and simultaneously upon opposite sides of said former-blocks, as set forth.

4. The combination, in a counter-stiffener 40 machine, of a wheel having rigid former-blocks upon its periphery, with a series of sliding blocks, and a corrugated plate having guide projections operated by springs, as and for the purpose set forth.

CHARLES LINUS TENNEY.
